UNITED STATES PATENT OFFICE.

JOSEPH S. WISHART, OF BROOKLYN, NEW YORK, ASSIGNOR TO WILLIAM JAMES HOGG & SON, OF WORCESTER, MASSACHUSETTS.

DESIGN FOR CARPET.

SPECIFICATION forming part of Design No. 27,450, dated July 27, 1897.

Application filed March 6, 1897. Serial No. 626,327. Term of patent 3½ years.

To all whom it may concern:

Be it known that I, JOSEPH S. WISHART, a citizen of the United States, residing at Brooklyn, in the county of Kings and State of New York, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such persons to use my invention.

The said drawing is a face view of a carpet embodying my new design. The drawing illustrates a body and a border.

The body A consists of a substantially uniform groundwork upon which appears a bunch of conventionalized flowers and leaves growing from an ornamental base and surrounded by leafy scrollwork, arranged to form a symmetrical figure of conventional form.

The border B consists of a groundwork 25 similar to that of the body, upon which appear sprigs of conventional flowers and leaves of similar character to those in the body. The outer edge is characterized by a band formed by scrollwork, which is surrounded by 30 arches of conventional flowers and leaves.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

J. S. WISHART.
